UNITED STATES PATENT OFFICE.

EMERY BÁRSÓNY, OF CASTLETON-ON-HUDSON, NEW YORK.

CIRCUIT-CLOSER FOR FIRE-ALARM SYSTEMS.

1,181,630.

Specification of Letters Patent.

Patented May 2, 1916.

Application filed April 22, 1915. Serial No. 23,085.

To all whom it may concern:

Be it known that I, EMERY BÁRSÓNY, a citizen of the United States, residing at Castleton-on-Hudson, in the county of Rensselaer and State of New York, have invented certain new and useful Improvements in Circuit-Closers for Fire-Alarm Systems, of which the following is a specification.

This invention relates to new and useful improvements in circuit closers for fire alarm systems.

The primary object of the invention is to provide a sensitive automatic thermal switch or circuit closer adapted for automatically closing upon the melting of a member carried by the switch, to complete a circuit and give an alarm, the circuit closer being adapted particularly for use in connection with fire alarm systems.

In the accompanying drawings which show the preferred embodiment of the present invention and to which reference is had herein by like characters designating corresponding parts throughout the several views:—Figure 1 is a sectional view through a circuit closer in accordance with this invention. Fig. 2 is a top plan view thereof.

A circuit closer in accordance with this invention is formed as illustrated in the drawing, being furnished with a di-electric base 21 adapted to be secured to a support as a wall 22. A rod 23 extends through the said base 21 and has a contact head 24 at one end thereof lying exposed and flush with the face 25 of one base while the said line wire 14 is connected to the said rod by means of a set screw 26.

A bracket 27 is secured by a screw 28 to the said base and has a switch lever 29 pivoted thereto and provided with a foot 30 for engaging the contact head 24. The other line wire 13 is positioned through an angular passage 31 of the base 21 and is secured to the switch lever screw 28. A coil spring 32 is provided in a recess 33 of the said base and engages the inner free end of the switch lever for normally influencing the contact foot 30 in engagement with the contact head 24 for completing the electrical connection between the line wires 13 and 14. A post 34 projects from the said base and is provided with a notch 35 adjacent the free end thereof while an arm 36 projects from the switch lever 29 and has a similar notch 37 in its opposite side. A fusible link 39 formed of any desired inflammable sub-

stance, such as pyroxylin, is provided for each switch having perforations 40 adjacent its opposite end and adapted for the reception therethrough of the free ends of 60 the said post 34 and arm 36, the notches 35 and 37 being thus positioned in hooked engagement by the fusible connector 39. A globe-shaped cap 41 may be positioned over the entire switch mechanism if desired for 65 the purpose of protecting such mechanism, this cap 41 being then formed of a similar fusible substance. It will be seen that in the event of a heating of the atmosphere to the desired degree which surrounds the switch, 70 the cap and the fusible link will become melted, the melting of the said link thus releasing the switch arm 36 and allowing the spring 32 to automatically close the switch lever in contact with the contact head 24. 75 This being done, will complete the circuit from the battery (not shown) which supplies the line wires.

What I claim as new is:—

1. A thermal switch comprising a supporting base, a contact rod positioned therethrough and having a head lying flush with one face of the said base, a bracket secured to said base face, a switch blade pivoted to the said bracket and having a contact foot in 80 normal engagement with the said head, resilient actuating means for the said blade, a post projecting from the said base, a link of highly inflammable material having perforations adjacent its opposite ends, a projecting arm carried by said switch blade and hooked over the free ends of the said post and arm, and a fusible cap mounted upon the said base and inclosing the said post and switch. 95

2. A thermal switch comprising an insulating supporting base, a contact rod extending through the base and having a head at one side of the base, a bracket mounted on said side of the base, a T-lever having one of the arms of the T pivoted intermediate its ends to the bracket, the remaining arm of the T being reversely curved to normally lie adjacent to but spaced from the rod head, said lever constituting a switch blade, a socket in said base adjacent the free end of the pivoted arm of the lever, a spring mounted in said socket and bearing against the free end of said pivoted arm to normally urge the remaining arm toward the rod head, a post rigidly fixed to said base in spaced relation to the lever and provided 100

with a notch facing away from said lever,
the stem of the lever being provided with a
similar notch facing away from the post,
and a fusible link having openings engaging
5 over the post and stem of the lever, the
notches coöperating with the edges of said
openings to prevent slipping of the link.

In testimony whereof I affix my signature
in presence of two witnesses.

EMERY BÁRSONY.
